UNITED STATES PATENT OFFICE.

ROBERT ANTHONY GILL, OF BERLIN, NEW HAMPSHIRE.

CUFF-LINK.

1,333,018.

Specification of Letters Patent.

Patented Mar. 9, 1920.

Application filed September 11, 1919. Serial No. 323,069.

To all whom it may concern:

Be it known that I, ROBERT A. GILL, a citizen of the Dominion of Canada, and a resident of Berlin, in the county of Coos and 5 State of New Hampshire, have invented certain new and useful Improvements in Cuff-Links, of which the following is a specification.

My invention is an improvement in cuff 10 links, and has for its object to provide a link of the character specified especially adapted for connecting link cuffs with the ends inclining toward each other instead of lapped in such a manner that they will be held in 15 such inclined position without bending of the cuff or danger of the breaking of the same when stiff cuffs are used.

In the drawings:

Figure 1 is a horizontal section through a 20 cuff at the link;

Fig. 2 is a perspective view of one of the links.

The present embodiment of the invention is shown in connection with a cuff 1^a having 25 buttonholes 2^a at its ends for receiving the link. The link, in the present instance, is stamped or cut from sheet metal of suitable character and weight.

The improved link is a substantially 30 U-shaped member, comprising a body 1 and arms 2 extending at an obtuse angle with respect to the body, that is, the arms diverge from each other. The link thus has a concave side and a convex side, and the convex 35 side is notched at the center, as indicated at 3, the notch having two branches 4 which extend substantially parallel with the curved edge of the link at the opposite sides of the center. Thus two heads 5 are formed, rigidly 40 connected, integral in the present instance,

whose planes are inclined to meet at something less than a right angle, and these heads are passed through the buttonholes as shown in Fig. 1, being of greater length than the length of the buttonholes.

45

The notches 3—4 in the present instance have ornamental outline, and it will be obvious that the outer faces of the heads might be suitably ornamented if desired.

A link of the character specified may be 50 cut or stamped from sheet metal, each link requiring but a single operation, and the links may be of any suitable material as, for instance, gold, silver, aluminum, or the links may be plated or filled with gold. The 55 links are easily inserted or removed, and because of the peculiar relation of the heads they hold the ends of the cuff in perfect shape without bending or danger of breaking.

60

I claim:

A cuff link comprising a body formed of sheet material stamped or cut to shape and comprising heads converging toward one end of the body, a shank connecting the 65 heads, a tongue extending from the side of the shank toward the converging ends of the heads and arranged with its edges in spaced relation to the adjacent edges of the heads whereby to define branch slots leading into 70 a common opening between the converging ends of the heads, the edges of said tongue and the adjacent edges of the heads being serpentine whereby to form portions extending toward each other in very close relation 75 for clamping engagement with the edges of a cuff within the button holes of which the device is engaged.

ROBERT ANTHONY GILL.
